UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

WARP STOP MOTION FOR LOOMS.

Application filed November 16, 1923. Serial No. 875,122.

To all whom it may concern:

Be it known that I, JONAS NORTHRUP, a citizen of the United States, residing at Hopedale, in the county of Worcester and State of Massachusetts, have invented certain new and useful Improvements in Warp Stop Motions for Looms; and I do hereby declare the following to be a full, clear, and exact description of the invention, such as will enable others skilled in the art to which it appertains to make and use the same.

The present invention relates to warp stop motions for looms.

The object of the invention is to provide a warp stop motion having provision for indicating the place of warp breakage, and to this end the invention consists in the warp stop motion hereinafter described and particularly defined in the claims.

In the accompanying drawings Fig. 1 is a side elevation, partly in section, of a warp stop motion embodying the features of the present invention; Fig. 2 is a front elevation of the warp stop motion; and Fig. 3 is a plan view illustrating the operation of the indicating means.

The illustrated embodiment of the invention comprises drop wires 6, each adapted to be supported by an individual warp thread, a frame 8 and a feeler bar 10. The feeler bar is connected through a lever 12 and link 14 to an oscillating part of the loom so that the detector is caused to oscillate below a pair of laterally extending angle irons 16 which form a part of the frame 8. On top of each angle iron 16 is secured a plate or stop bar 18 which extends over the edge of the angle iron 16 and is adapted to be engaged by a fallen drop wire when the latter is struck by the detector.

Heretofore it has been customary to engage the fallen drop wire between the feeler 10 and the angle iron 16. However, since the angle iron is situated immediately above and close to the path of oscillation of the feeler, the drop wire maintains its position parallel to the other drop wires and thus fails to give an indication of the place of warp breakage. In view of the large number of warps it takes time to locate the broken warp when this prior form of warp stop motion is used. According to the present invention, the engagement of the drop wire between the feeler 10 and the plate 18

which is situated an appreciable distance above the feeler causes a slight turning or twisting of the drop wire around a vertical axis, thereby spreading the adjacent drop wires slightly as indicated in Figs. 2 and 3. This gives a positive indication of the place of warp breakage which is readily noticeable by the weaver, thereby enabling him to repair the broken thread and start the loom in a minimum of time.

Although the action of the fallen drop wire when engaged by the feeler is not perfectly understood, it is believed to take place in the following manner:—If the drop wire is engaged between points of approximately equal height, as by the feeler 10 and the angle bar 16 as in prior forms of warp stop motions, there is no tendency for distortion of any part of the drop wire. However, if the drop wire is engaged between points which are an appreciable distance apart, as by the feeler and stop bar in the present invention, the drop wire, being of light construction, is caused to undergo a definite distortion at its lower portion between the feeler and stop bar. The drop wire is twisted about a vertical axis; the lower portion is turned by a considerable amount, while the upper portion being limited in movement by the supporting bar and the pressure of the adjacent drop wires, inclines at a less degree. This causes the edges of the lower portion of the drop wire to be angularly presented to the feeler and stop bar so that upon the continued pressure of the feeler the edges of the drop wire may slide over the engaging surfaces into an even more inclined position. This is in effect a turning movement of the drop wire about its vertical axis.

While it is preferred to employ the specific construction and arrangement of parts shown and described, it will be understood that this construction and arrangement is not essential except so far as specified in the claims and may be changed or modified without departing from the broader features of the invention.

The invention having been described, what is claimed is:

1. A warp stop motion for looms having, in combination, drop wires having slots at their upper ends, a drop wire bar in the slots, a feeler adapted to engage with the

lower end of a fallen drop wire, and stationary means cooperating with the feeler above the latter to turn the drop wire to spread the warp on either side thereof to indicate the place of warp breakage.

2. A warp stop motion for looms having, in combination, drop wires having slots at their upper ends, a drop wire bar in the slots, a feeler bar adapted to engage the lower

end of a fallen drop wire, and a stop bar 16 located above the feeler for engaging the drop wire and arranged a sufficient distance from the feeler bar to impart a turning movement to the drop wire in a manner to spread adjacent drop wires and indicate the 15 place of warp breakage.

JONAS NORTHROP.
